Attorney

UNITED STATES PATENT OFFICE.

FRANK MITCHELL, OF ST. JO, TEXAS.

PLATE-LIFTER.

1,239,615.

Specification of Letters Patent. Patented Sept. 11, 1917.

Application filed February 28, 1917. Serial No. 151,557.

To all whom it may concern:

Be it known that I, FRANK MITCHELL, a citizen of the United States, residing at St. Jo, in the county of Montague and State of Texas, have invented certain new and useful Improvements in Plate-Lifters, of which the following is a specification, reference being had to the accompanying drawings.

10 This invention relates to certain improvements in plate lifters and it is an object of the invention to provide a device of this general character of a novel and improved construction and including means where-
15 by a plate to be lifted may be effectively clamped.

The invention consists in the details of construction and in the combination and arrangement of the several parts of my im-
20 proved lifter whereby certain important ad-
vantages are attained and the device is
rendered simpler, less expensive and other-
wise more convenient and advantageous for
use, all as will be hereinafter more fully set
25 forth.

The novel features of the invention will
hereinafter be definitely claimed.

In order that my invention may be the
better understood, I will now proceed to de-
30 scribe the same with reference to the accom-
panying drawings, wherein—

Figure 1 is a view in elevation of a plate
lifter constructed in accordance with an em-
bodiment of my invention;

35 Fig. 2 is an enlarged fragmentary view
in elevation of the handle members as here-
in embodied;

Fig. 3 is a view in perspective of the grip-
ping end portion of a second handle member
40 as herein included; and

Fig. 4 is an enlarged fragmentary view
in perspective of the plate engaging portion
of a third handle member as herein dis-
closed.

45 As disclosed in the accompanying drawings,
A denotes an elongated handle member
which is formed by doubling a single
length of wire upon itself and twisting the
strands thereof one about the other the
50 major portions of their lengths with the
free end portions of said strands formed
into the diverging arms 1 terminating in
the depending and substantially perpen-
dicularly related extensions 2 which are
55 continued in the forwardly extending mem-
bers 3 arranged in a plane substantially

parallel to the plane of the handle. As is
believed to be self-evident the extensions 2
are adapted to underlie the plate or the like
to be lifted.

B denotes a second handle member also
formed of a single length of wire returned
upon itself and having the strands twisted
one about the other substantially the major
portion thereof and the free end portions
60 of the strands of said handle B are also ar-
ranged in diverging relation, as indicated at
4, and terminate in the angular extensions 5
disposed in a direction toward the extensions
3 of the handle member A.

At a point inwardly of the diverging por-
tions 4 the strands of the handle member B
are coiled to afford the transversely alined
eyes 6 arranged at opposite sides of the
handle member B and in register with the
75 loop or eye 7 afforded by a separated por-
tion of the strands comprised in the handle
member A. The eye 7 is also positioned in
close proximity to its diverging arms 1.

Disposed through the eyes 6 and 7 is the
80 pintle 8 whereby it will be perceived that
the handles A and B are maintained in
crossed relation and are also capable of rela-
tive swinging movement. In practice the
diverging portions or arms 4 overlie the
85 flange of a plate or pan with the depending
portions 5 extending within said plate or
pan which results in an effective clamping
action upon the plate or pan when the outer
90 ends of the handles A and B are moved one
toward the other.

To further assure the requisite engage-
ment with the plate or pan to be lifted I find
it of manifest advantage to provide the
95 third handle C preferably of a length ma-
terially less than the length of the handles
A and B. The handle C is also produced by
returning a single length of wire and twist-
ing the strands thereof one about the other,
and one of said strands immediately in ad-
100 vance of the twisted portion of the handle is
coiled upon itself to afford an eye 9 adapted
to be positioned between the eyes 6 of the
handle member B and through which the
pintle 8 is also disposed whereby said 105
handle member C is mounted for rocking
movement. The strand provided with the
eye 9 is extended forwardly a distance suffi-
cient to terminate between the outer ends
of the diverging portions or arms 4 of the 110
handle B and terminates in an inwardly di-
rected hook portion 10 which is adapted to

underlie the flange or rim of a plate or pan to be lifted at a point intermediate the arms 1 and 4 so that when the handle C is moved inwardly toward the handles A and B, a 5 further gripping action is had upon the plate or pan to be lifted and which results in holding the plate or pan steady.

From the foregoing description, it is thought to be obvious that a lifter constructed in accordance with my invention is of an extremely simple and comparatively inexpensive nature and is particularly well adapted for use by reason of the convenience and facility with which it may be assembled, 10 and it will also be obvious that my invention is susceptible of some change and modification without material departure from the principles and spirit thereof and for this reason I do not wish to be understood as 15 limiting myself to the precise arrangement and formation of the several parts herein shown in carrying out my invention in practice, except as hereinafter claimed.

I claim:

25 1. A device of the character described comprising two handle members in crossed relation, means for pivotally connecting the crossed portions of the handles, one end portion of the handle being provided with 30 spaced extensions adapted to underlie a plate, the adjacent end portions of the second handle being provided with arms adapted to overlie the rim portion of a plate or the like and terminating in angular extensions disposed toward the extensions of the 35 first handle member, and a third handle member mounted intermediate its length for pivotal movement and having an end portion interposed between the extensions of 40 the first named handles and adapted to engage beneath the rim of the plate.

2. A device of the character described comprising two handle members in crossed relation, means for pivotally connecting the 45 crossed portions of the handles, one end portion of the handle being provided with spaced extensions adapted to underlie a plate, the adjacent end portions of the second handle being provided with arms adapted to overlie the rim portion of a plate or the like and terminating in angular extensions disposed toward the extensions of the 50 first handle member, and a third handle member mounted intermediate its length for

pivotal movement and having an end portion interposed between the extensions of the first named handles and adapted to engage beneath the rim of the plate, said third named handle being movable about the same pivotal point as the first two handle members. 55

3. A device of the character described comprising two handle members in crossed relation, each of said handle members being formed of a single length of material returned upon itself and having the major portion of the strands twisted one about the other, the strands of one of the members being coiled to afford transversely spaced eyes, and a twisted portion of the second handle member being separated to afford loops adapted to be interposed between the eyes of the first named handle member, a pivot pin disposed through the eyes of the handle members, the free end portions of the 75 strands of one of the handle members being in diverging relation and provided with extensions adapted to underlie a plate, the free extremities of the second handle member being also provided with diverging arms 80 adapted to overlie the rim portion of a plate and terminating in extensions disposed toward the extensions of the first named handle, and a third handle member pivotally engaged intermediate its length with the 85 pin, an end portion of said third handle member extending between the diverging arms of the first named handle member and adapted to underlie the rim portion of a plate. 90

4. A device of the character described comprising three handle members pivotally connected at a common point, two of said handle members being in crossed relation, one of said crossed handle members having 95 an end portion adapted to underlie a plate, the adjacent end portion of the second crossed handle member being adapted to overlie the rim portion of a plate and the adjacent end portion of the third handle member being also adapted to underlie the 100 rim portion of a plate.

In testimony whereof I hereunto affix my signature in the presence of two witnesses.

FRANK MITCHELL.

Witnesses:

JOHN MASS,
I. BATEMON.
